UNITED STATES PATENT OFFICE.

WILLIAM D. SLATER, OF SPRINGFIELD, MASSACHUSETTS, ASSIGNOR TO UNITED STATES ENVELOPE COMPANY, OF SPRINGFIELD, MASSACHUSETTS, A CORPORATION OF MAINE.

ENVELOP-MACHINE.

No. 923,720.

Specification of Letters Patent.

Patented June 1, 1909.

Application filed July 31, 1906. Serial No. 328,633.

To all whom it may concern:

Be it known that I, WILLIAM D. SLATER, a citizen of the United States, residing at Springfield, in the county of Hampden and 5 Commonwealth of Massachusetts, have invented a new and useful Improvement in Envelop-Machines, of which the following is a specification, accompanied by drawings, forming a part of the same, in which—
10 Figure 1 represents a plan view of so much of an envelop machine as is necessary to illustrate the nature and operation of my present invention. Fig. 2 is a front view of the same. Figs. 3, 4 and 5 are detail views on a 15 larger scale of portions of the mechanism for applying a transparent patch to cover an opening in the envelop blank.
15 Similar reference figures refer to similar parts in the different views.

20 My present invention relates to that portion of the mechanism of an envelop machine which is directly concerned in applying a transparent patch to an opening in the body portion of an envelop blank by which an address printed upon an inclosure in the envelop may be read from the outside.
25 In the accompanying drawings I have shown only such portions of an envelop machine as are necessary to illustrate my present invention.

30 The mechanism embodying my present invention is designed to be operated in connection with the gumming and folding mechanisms of an envelop machine in which gum is applied to the uppermost blank in a pile or 35 stack of blanks 1, supported upon a feed table 2 and the gummed blank is transferred by a reciprocating carriage 3 over the rectangular opening 4 of a folding or creasing box, 40 through which opening the blank is pushed by a reciprocating plunger as is common in envelop machines now in use. Mounted upon the table 5 and between the feed table 2 and the folding box 4 I mount the mechanism 45 embodying my present invention for applying to the envelop blank a transparent patch to cover an opening 6 formed in the body portion of the envelop, and in the position usually occupied by the address.

50 The envelop blank when presented to the mechanism for applying a patch to cover the opening 6 has been supplied with a narrow margin of adhesive material around the opening 6, and in its passage from the table 2 to the folding box 4 by means of a recipro-

cating carriage 3 is given a period of dwell above a pressing bed 7 mounted upon the table 5. Mounted upon the table 5 are curved brackets 8, 8, provided with ways 9 for a reciprocating frame 10, provided on its under side with a yielding presser plate 11, said presser plate being given a reciprocating motion by means of a rocking lever 12, link 13, and cam 14 on the driving shaft 15, by which the presser plate is carried down to 60 65 coöperate with the bed 7 to press a patch upon the gummed surface of the envelop blank and over the opening 6. Mounted in arms 16 depending from one of the brackets 8 is a reel 17 containing a continuous strip 18 70 of transparent paper which passes between feed rolls 19 and 20. An intermittent motion is given to the feed rolls 19 and 20 by means of a pawl 21, carried upon a rocking lever 22, which is connected by a link 23 with 75 a swinging lever 24 actuated by a cam 25 upon a vertical shaft 26 connected by gears 27 with the driving shaft 15. By the intermittent movement of the feed rolls 19 and 20 the continuous transparent strip 18 is projected forward over a stationary shear plate 28 which acts in conjunction with the end of the yielding presser plate 11 to sever the transparent strip.

80 Sliding upon ways 29 is a carriage 30 connected by a link 31 to a lever 32 which is actuated by a link 33 and cam 34 on the vertical shaft 26. The carriage 30 carries a gripping mechanism comprising a jaw 35 attached to the carriage, and a jaw 36 attached to a rocking shaft 37 journaled in the carriage 30. The jaw 36 is normally held in contact with the jaw 35 by means of a blade spring 38. Attached to one end of the rocking shaft 37 is an arm 39 carrying in its free 95 end a stud 40 which passes beneath an inclined cam plate 41 attached to the framework of the machine, causing the arm 39 to be depressed and the shaft 37 to be rocked against the tension of the blade spring 38 in 100 order to open the jaws 36 and 35 to release the paper strip.

When the arm 39 is depressed to open the gripping jaws a pawl 42 is carried into engagement with a shoulder 43 on the arm 39 105 by means of a blade spring 44. The pawl 42 serves to maintain the arm 39 in its depressed position and hold the gripping jaws open during the reverse movement of the carriage 30 along the ways 29. As the carriage 110

30 approaches the opposite end of its travel an arm 45 attached to the pawl 42 is carried beneath an inclined cam plate 46 causing the arm 45 to be depressed and the pawl 42 to be 5 raised out of engagement with the shoulder 43, thereby allowing the blade spring 38 to close the gripping jaws and seize the end of the continuous paper strip 18 which has been fed slightly beyond the edge of the shear 10 plate 28 by the action of the feed rolls 19 and 20. When the end of the continuous strip 18 has been seized by the gripping jaws the carriage 30 is moved forward drawing after it the strip of transparent paper over the 15 gummed envelop blank resting upon the pressing bed 7. The movement of the carriage beneath the inclined cam plate 41 opens the gripping jaws and releases the paper strip which is then severed by the downward movement of the pressing plate 11 as it 20 passes the shear plate 28, the continued downward movement of the pressing plate causing the severed strip to be pressed upon the gummed surface of the envelop blank and 25 over the opening 6. The pressing plate 11 then rises and the continuous strip 18 is projected forward by the feed rolls 19 and 20, actuated by the cam 25, to move the end of the strip 18 sufficiently beyond the cutting 30 edge of the shear plate 28 to enable it to be seized by the gripping jaws 36 and 35. The envelop blank with a patch applied thereto is then in condition to be moved forward by the reciprocating carriage 3 over the folding 35 box 4.

The mechanism by which the operation of gumming the blanks upon the feed table 2; folding the blanks at the folding box 4, and transferring the gummed blanks to the folding 40 box and over the pressing bed 7, forms no part of my present invention, and these portions of the operating mechanism of an envelop machine are not shown, as they are well known and familiar to those conversant 45 with this class of machines. Mechanisms by which all of these usual operations can be performed are fully shown and described in the United States Patent No. 401,462, issued to A. A. Rheutan, April 16, 1889.

50 I claim,

1. In a machine of the character described, the combination with a feed table for the blanks, a folding box and a reciprocating carriage for transferring the blanks from the 55 feed table to the folding box, of a blank supporting table and a reciprocating presser plate coöperating with said table, a cutting mechanism for severing a patch from an endless strip, rolls for feeding the endless 60 strip beyond the cutting mechanism in position to be seized by gripping jaws, a second reciprocating carriage, means for moving said second carriage transversely to said first carriage, gripping jaws held by

said carriage, a spring for closing said jaw, 65 means for opening said jaws at one end of their travel, means for holding said jaws open during their reverse movement, and means for releasing said jaws to seize the strip at the opposite end of their travel. 70

2. In a machine of the character described, the combination with the feed table, folding box and carriage for transferring the envelop blanks from said feed table to said folding box, of a pressing mechanism between, 75 the feed table and folding box, means for supporting a continuous strip of paper at one side of said pressing mechanism, a cutting mechanism for severing the continuous strip, feed rolls for projecting the end of the 80 continuous strip beyond said cutting mechanism, a gripping mechanism for seizing the end of the continuous strip, means for moving said gripping mechanism past said pressing mechanism and transversely to said 85 carriage.

3. In a machine of the character described, the combination with the feed table, folding box and carriage of an envelop machine, of a roll for supporting a continuous strip of 90 paper, feed rolls for feeding said strip, means for imparting an intermittent motion to said rolls, a cutting mechanism for severing said continuous strip, a pair of gripping jaws, means for imparting a reciprocating 95 movement to said jaws transversely to the movement of said carriage and in alinement with said feed rolls, means for opening and closing said jaws at opposite ends of their reciprocating movement, and a pressing 100 mechanism located between the feed table and folding box.

4. In a machine of the character described, in combination with the feed table, a folding box, a reciprocating carriage for feeding, transferring and folding envelop blanks, of a pair of feed rolls having an intermittent motion for feeding a continuous strip transversely to the line of movement of said reciprocating carriage, a pair of reciprocating 105 jaws moving in alinement with said feed rolls, means for opening said jaws at one end of their travel, means for holding said jaws open during their return movement, means for closing said jaws at the opposite end of 110 their travel, a cutting mechanism between said feed rolls and said reciprocating jaws for severing said continuous strip, and a pressing mechanism for applying the severed pieces to the envelop blank. 115

5. In a machine of the character described, the combination with a support for a pile of envelop blanks, means for folding an envelop blank and means for transferring an envelop blank from said support to said folding means, of a pair of feed rolls having an intermittent motion for feeding a continuous strip transversely to the line of movement of 120 125

the envelop blank from said support to said folding means, a pair of gripping jaws arranged to reciprocate in alinement with said feed rolls, means for imparting a reciprocating movement to said jaws, means for severing said continuous strip between said feed rolls and said gripping jaws, and means for

applying said severed piece to the envelop blank.

Dated this eleventh day of July 1906.

WILLIAM D. SLATER.
